UNITED STATES PATENT OFFICE.

LEWIS WARD, OF WICHITA, KANSAS, ASSIGNOR TO MERGENTHALER LINOTYPE COMPANY, A CORPORATION OF NEW YORK.

ADJUSTABLE LINER FOR LINOTYPE-MACHINES.

No. 826,349.

Specification of Letters Patent.

Patented Nov. 20, 1906.

Application filed April 30, 1904. Serial No. 205,705.

To all whom it may concern:

Be it known that I, LEWIS WARD, a resident of Wichita, in the county of Sedgwick and State of Kansas, have invented certain new and useful Improvements in Adjustable Liners for Linotype-Machines; and I do hereby declare the following to be a full, clear, and exact description of the invention, such as will enable others skilled in the art to which it appertains to make and use the same.

My invention relates to an improvement in adjustable slotted molds such as are used in linotype-machines to form the linotype-slugs or line-printing bars, the object being to permit the adjustment of the mold in order to vary the size of its slot and of the slugs cast therein in a cheaper and more simple manner than heretofore practiced.

As shown, for example, in Letters Patent of the United States No. 620,804, linotype-molds consist of a body portion, an overlying cap, and two intermediate liners or spacing pieces, which determine both the length and the width of the slot.

Heretofore it has been the usual practice to effect a change in the length of the mold-slot by removing the liner at one end and substituting another of different length.

When a change in the width of the slot was required, both liners were removed and replaced by others of a thickness corresponding to that of the required slug. This practice necessitated the employment of a large number of expensive liners in order to meet the various requirements of the printer. To overcome this difficulty, I make use of composite liners, adjustable in length and also adjustable in thickness, so that a single liner will serve to adjust the mold-slot at one end both as to length and width.

The details of construction may be variously modified without departing from the limits of my invention.

In the accompanying drawings I have represented a construction which in practice has given good results.

Figure 1 represents a front elevation of a linotype-mold having my improved liner therein. Fig. 2 is a perspective view of a mold, showing the members of the mold and liner separated. Figs. 3, 4, and 5 are perspective views showing the various parts of the liner.

Referring to the drawings, 1 represents the body or base portion of the mold 2, the overlying adjustable cap, and 3 a liner located between the cap and body, with a transverse rib fitting into the latter and serving to determine the distance between them and also to form one end of the mold slot or cell 15, in which the slug or linotype is cast.

The foregoing parts are of ordinary construction. The cap and body must be separated by liners at both ends. Heretofore it has been customary to employ at the left a solid liner similar to the liner 3. Instead of using a second solid liner I provide a composite liner, consisting of the principal members *a* and *b* and one or more supplemental members 10. The parts *a* and *b* constitute the main portion of the liner and are to be used without the supplemental members for casting thin slugs. The part *a* is constructed with a transverse rib 5, seated in a corresponding recess in the body of the mold for the purpose of holding it against longitudinal movement and of keeping it properly in line. The outer or thicker end of this liner is of the same thickness as the liner 3 and determines the distance between the mold-cap and body. The inner end 6 of the member *a* is reduced in width and in thickness, so that it forms a long horizontal tongue. The member *b* has its inner end and longitudinal edges of the same thickness as the outer end of the member *a* and is formed in its upper face with a longitudinal groove adapted to receive the tongue 6 of the member *a*, and also provided with a series of holes or notches 9, to receive a stud 8 on the tongue. When the tongue of the member *a* is seated in the groove of the member *b*, the two constitute jointly a liner of variable length, which may be seated between the cap and the mold and the inner end of which will form one end of the mold slot or cell, as shown in Figs. 1 and 2.

When the length of the slot is to be increased or diminished, the liner is removed edgewise from the mold, or released by lifting the mold-cap, and the member *b* moved forward or backward in relation to the member *a* until the distance between the inner ends of the two liners equals the length of the required slug. The holes 9 are commonly spaced an em or half-em apart in order to facilitate the adjustment of the mold-slot in accordance with the accepted printer's meas-

ure or standard. As regards the liner of variable length, it is only necessary that its members should be made in such form and connected in such manner that the inner end should be movable forward and backward at will to vary the length of the mold-slot. It will be seen that the member *a* serves not only to aid in supporting the cap and determining the width of the mold-slot, but also to guide the movable member *b* and prevent it from moving either endwise or edgewise out of the required position.

When it is required to change the vertical width of the mold-slot in order to produce slugs of another thickness, I use one or more of the supplemental plates or liners 10, seating the same on top of the members *a* and *b*, as shown in the drawings. This supplemental plate is provided with studs 11, adapted to enter corresponding holes in the member *b*, whereby it is kept in proper position thereon. The inner or operative ends of the members *b* and 10 are of like form and stand in line, so that they jointly form the end of the mold slot or cell. There may be any desired number of the plates 10, of the same or of different thickness, and they may be placed one upon another.

When the adjustable liner is varied in thickness, as described, which may be done without changing its length, the liner 3 is removed and another of a thickness corresponding to that of the composite liner inserted. Instead of replacing the liner 3 by another of different thickness the supplemen-

tal plates 10, of suitable form, may be used thereon to increase its thickness, as in the case of the composite liner.

When the liner is extended, as shown in Fig. 2, a space is left between the outer end of the member *b* and the thick end of the portion *a*. It may happen that molten metal will be delivered into this space; but this will be of no moment, since the metal will solidify and fill the space without interfering with the operation of the machine.

What I claim as my invention is—

1. A linotype-mold, comprising cap and body portions and a composite liner variable in thickness, substantially as shown.
2. A linotype-mold comprising a liner variable in thickness and in length, substantially as described.
3. A liner for a linotype-mold, comprising a plurality of separable sections, seated one upon another, whereby it may be definitely varied in thickness.
4. A linotype-mold consisting of cap and body portions and an intermediate liner consisting of a fixed member and two separable longitudinally-movable members co-operating with the fixed member, substantially as shown.

In testimony whereof I have signed this specification in the presence of two subscribing witnesses.

LEWIS WARD.
